UNITED STATES PATENT OFFICE.

VICTOR FREISINGER, OF ATLANTIC CITY, NEW JERSEY.

DESIGN FOR A SPOON OR FORK.

No. 38,258.

Specification for Design.

Patented Oct. 2, 1906.

Application filed August 16, 1906. Serial No. 330,933. Term of patent 7 years.

To all whom it may concern:

Be it known that I, VICTOR FREISINGER, a citizen of the United States, residing at Atlantic City, in the county of Atlantic and State of New Jersey, have invented a new, original, and ornamental Design for Spoons and Forks, of which the following is a specification, reference being had to the accompanying drawings, forming part thereof, which illustrate the application of my design to the handle of a spoon or fork, and in which—

Figure 1 is a front plan view, and Fig. 2 is a rear plan view.

It will be understood that the dotted lines in both figures showing the outline of a fork indicate that my design may be applied to the handle of a fork as well as to that of a spoon.

I claim—

The ornamental design for a spoon or fork as shown.

VICTOR FREISINGER.
